UNITED STATES PATENT OFFICE.

DANIEL WILLIAM SHEA, OF TAMPA, FLORIDA, ASSIGNOR TO THE SUBMARINE SALVAGE COMPANY OF AMERICA, OF WILMINGTON, DELAWARE, A CORPORATION OF DELAWARE.

SUBMARINE-SALVAGE APPARATUS.

1,188,333.

Specification of Letters Patent. Patented June 20, 1916.

Application filed February 5, 1916. Serial No. 76,394.

To all whom it may concern:

Be it known that I, DANIEL WILLIAM SHEA, a citizen of the United States, residing at Tampa, in the county of Hillsboro 5 and State of Florida, have invented certain new and useful Improvements in Submarine-Salvage Apparatus; and I do hereby declare the following to be a full, clear, and exact description of the invention, such as 10 will enable others skilled in the art to which it appertains to make and use the same.

My invention relates to improvements in apparatus for indicating and raising sunken boats, and it is especially intended to provide 15 vide apparatus whereby sunken submarines may be indicated and raised.

The said invention is intended to provide improvements in certain features shown in the U. S. patent to John F. Shea, entitled 20 "Means for indicating and raising sunken boats", granted May 23, 1911, No. 993205. According to the invention shown in that patent, and also in the following specification, the pilot line is coiled in a suitable 25 receptacle carried by the boat, and to the ends of this line, respectively, a large and a small float are attached. The bight of the line passes over a pulley, and when the buoys are released they rise upward through 30 the water, carrying upward the ends of the pilot line, and if the water is shallow both floats will float upon the surface of the water; while if the water is deep the upper float will rise to the surface, or as far up to 35 ward the surface as possible, and the smaller float will be held down by the greater lifting effect of the large float.

When the upper float is released from the pilot line, and a lifting cable attached 40 thereto, the cable will sink and the smaller float will rise to the surface, and the pilot line may be used to draw the end of the cable under the pulley, as described in the patent aforesaid. It has been found, how- 45 ever, in practice, that it is very difficult to provide a float which will have sufficient buoyancy to accomplish the purposes sought, and yet may be subjected to the pressure of the water at such depth as the sunken boat is 50 likely to descend; and this invention relates especially to the construction of the floats,

whereby a comparatively light float may be secured which will have sufficient buoyancy, and at the same time will be able to stand the pressure of the water at the depth to 55 which the boat is sunk. Of course, an apparatus of this character is capable of and intended for use only on soundings, and where the water is comparatively shoal, say not over a few hundred feet in depth. 60

My invention will be understood by reference to the accompanying drawings, in which:

Figure 1 is a plan view of the chamber or chest provided in the upper portion of the 65 body of the boat, and containing the buoys, the pilot line, and the pulley; Fig. 2 shows a section along the broken line 2-2 of Fig. 1, and looking in the direction of the arrows; Fig. 3 shows a section along the line 3-3 70 of Fig. 2, and looking down; Fig. 4 shows a central vertical section through the pulley, said section being indicated by the line 4-4 of Fig. 3; Fig. 5 is a plan view, partly in horizontal section, of the smaller buoy, the 75 section being along the line 5-5 of Fig. 6; Fig. 6 is an elevation, partly in section, of the smaller buoy, the section being along the line 6-6 of Fig. 5; Figs. 7 to 13 show details of construction of the larger buoy. 80 Fig. 7 shows a side elevation of the buoy; Fig. 8 is a plan view, partly in section, along the line 8-8 of Fig. 9; Fig. 9 shows a section along the line 9-9 of Fig. 8, and looking in the direction of the arrows; Fig. 10 85 shows a section along the line 10-10 of Fig. 8, and looking in the direction of the arrows; Fig. 11 shows a detail of one of the internal braces taken along the line 11-11 of Fig. 10, and looking down, the parts 90 being shown on a larger scale; Fig. 12 shows a section along the line 12-12 of Fig. 11, looking in the direction of the arrows, and parts being shown in elevation; Fig. 13 shows a section along the line 13-13 of Fig. 95 11, looking in the direction of the arrows, and parts being shown in elevation; Fig. 14 is a cross section showing one of the butt welded joints; and Fig. 15 is a section showing one of the lap welded joints. 100

A represents the hull plating of the submarine, see Figs. 2 and 4, which is rein-

forced in the usual way as by means of the angle beams A', and is also provided with suitable special reinforces, such as the bands B and B', see Figs. 2, 3 and 4.

5 C represents a pedestal secured to the hull of the boat, and provided with a bearing ring C' having a ball race for the balls E. Mounted above this ring is the ring D', resting on said balls E, which ring is secured to the housing D, in which the pulley F is mounted. This housing D has its ends flared, as at D°, to provide a fairway for the pilot line J which passes over said pulley. The pulley F is journaled on the pin G, secured in the yoke H, fitting against the sides d of the housing D, as shown most clearly in Fig. 4.

10 The head i of the king bolt I engages in this yoke H and, passing through the reinforcing bands B and B' and the hull plating A, is secured in place in any suitable way as by the nut I'.

15 The ends of the pilot line J are attached to the eyes m of the larger buoy M, and n of the smaller buoy N, and the bight J' of this line is coiled up in the channel formed by the supporting blocks O for the smaller buoy and the walls p and p' of the buoy chamber P, which is formed between the 20 hull plating of the submarine and the deck plating Q. The special construction of the buoys will be hereinafter more fully described.

25 Closing the top of the buoy chamber, and flush with the deck Q, is the top plate M° of the upper and larger buoy M. This forms a cover for the buoy chamber flush with the deck Q. This plate has slotted hinges at one end, as at m°, engaging the heads s of the 30 T-shaped bolts S, and at the other end this plate is provided with a slotted lug m', into which slot projects the head t of the T-bolt T, which head is also flush with the deck, as shown in Fig. 2. This bolt may be 35 turned from the interior of the boat by the hand wheel T', so as to turn the head t into the unlocking position, and this may also be accomplished automatically by the pressure of the water when the boat sinks to a predetermined depth, as described in the patent 40 to John F. Shea, No. 993205, aforesaid.

45 In Figs. 1, 2, 3 and 4 I have shown the buoys diagrammatically for clearness in the drawings, but in Figs. 5 and 6 I have shown the preferred manner of constructing the smaller buoy, while in Figs. 7 to 13 I have shown the preferred manner of constructing the larger buoy, as will now be described.

50 The larger buoy consists of a main body portion 1, substantially rectangular in shape but with rounded corners 2, and with two longitudinally-projecting legs 3 and 4 which straddle the housing D for the pulley F when the apparatus is in the assembled po-

sition shown in Fig. 2. The top of the main body portion and of these longitudinally-projecting legs, and of the opening between said legs, is closed over by the plate M°, which plate is ribbed or corrugated where it forms the wall of the air chamber of the buoy, as at 5, and may be left plane, as at 6, where it forms merely a part of the deck surface of the boat. By this arrangement the top plate of the larger buoy forms a part of the deck surface of the boat, and flush with the deck. The sides and bottom wall of the boat are formed of a series of plates provided with ribs or corrugations, and these plates are also provided with suitable trusses, such as the trusses 7 in the main body portion of the buoy M, the trusses 8 and 9 in the ends thereof, and the trusses 10 and 11 in the legs thereof. In the main body portion, the buoy is also provided with bracing in the form of hollow tubes 12, made 55 preferably of strong and light material, such as vanadian steel. These tubes extend between the top and bottom walls of the body portion of the buoy and stiffen same against compressive strains. The ends of 60 these tubes engage in sockets 13, formed of two separate blocks connected by the bolts 14 to the web 15 of the truss 7, as shown in Figs. 10 to 13. These vertical bracing tubes are shown in Figs. 8 and 10, but are omitted 65 from Fig. 9 for the sake of clearness in the drawings.

65 Reverting now to the construction of the smaller buoy, shown in Figs. 5 and 6, this is preferably substantially rectangular in 70 cross section but with rounded corners as shown. In constructing this buoy I provide top and bottom plates 20 and 21, rounded as shown, and each provided with corrugations 22, which top and bottom plates 75 are braced by the vertical bracing tubes 23 similar to those already described in connection with the larger buoy. Connected to the ends of these top and bottom plates are the four corner plates 24, curved as shown, 80 and inclosing the inner edges of these top and bottom plates and corner plates is the band 25, corrugated as at 26. This band is also braced by the longitudinal tubes 27 85 and transverse tubes 28, as shown in Figs. 110 5 and 6. All of the joints in both of the buoys are electrowelded to form an air and water tight joint, as shown in Figs. 14 and 15.

90 The operation of the device is as follows:—Suppose the boat to be sunk, and the locking bolt T to be released either by hand or automatically as described, the larger buoy M will lift, swinging about the hinges m° until these are released and the buoy is 95 free to move upward through the water due to its buoyancy. As soon as the buoy M is out of the way, the smaller buoy N also

floats upward, and the pilot line pays out as the buoys rise. The pulley F, being mounted on a universal joint, turns to always give a fair lead to the pilot line, it 5 being free to turn in any direction horizontally as soon as the larger buoy has floated clear of the boat. If the water is shallow, both buoys will rise to the surface, but if the water is deep the larger buoy 10 will rise to, or approach, the surface, dragging down the smaller buoy and holding it in the submerged position. As soon as the pilot line is detached from the larger buoy, and fastened to a hoisting cable, and the 15 latter is let go, this will release the smaller buoy, which will rise to the surface bringing with it the pilot line, and the hoisting cable may be rove thereby beneath the pulley sheave, and the boat may be lifted by 20 hauling up on one end of this hoisting cable, making fast the other end to the relief vessel. Where the boat to be lifted is heavy, of course, several sets of salvage apparatus as herein described would be employed. Thus, for a submarine of the ordinary size two or more such apparatus may 25 be used, located at the proper parts of the hull of the boat.

It will be seen that the herein-described 30 apparatus is countersunk between the upper deck of the boat and the hull proper, but does not offer any obstruction either to the boat's progress through the water, or to the free movement of the crew along the deck; 35 and by having the top plate of the main buoy flush with and forming a part of the upper deck of the boat, the apparatus forms a part of the superstructure of the boat, is not in the way, and yet is completely detachable therefrom when emergency requires.

By having the buoy chamber P with sloping sides, as shown in Fig. 3, the buoy is not apt to stick therein, and the pilot line is provided with a fair lead from every side 45 of the chamber.

By having the larger buoy with legs as shown, I not only secure the added buoyancy of these legs, which are very rigid, being of small and arch-shaped cross section; but I also make use of the space on 50 each side of the housing D containing the pulley F, and on modern submarines any saving of space is an important factor.

By having the buoys corrugated and 55 braced, as shown, they are able to stand the heavy pressure such as exists at a depth of several hundred feet below the sea level, or at the maximum depth from which it would be practicable to lift such boats and 60 save the crew.

It will be obvious that various modifications might be made in the herein described apparatus, and in the construction, combination and arrangement of parts which could

be used without departing from the spirit 65 of my invention.

Having thus described my invention what I claim and desire to secure by Letters Patent of the United States is:—

1. Apparatus of the character described, 70 comprising a chamber provided on the upper side of the boat, a pulley mounted in said chamber, a pilot line rove over said pulley and also mounted in said chamber, and a pair of buoys connected, respectively, to 75 the ends of said pilot line, said buoys being of unequal buoyancy, and the upper buoy being provided with longitudinally-projecting legs straddling said pulley, and having its top formed of a plate forming a cover 80 for said chamber, substantially as described.

2. Apparatus of the character described, comprising a chamber provided on the upper side of the boat, said chamber being located between the upper deck and the top of 85 the hull of said boat, and having its top flush with the upper deck, a pulley mounted in said chamber, a pilot line rove over said pulley and also mounted in said chamber, and a pair of buoys connected, respectively, 90 to the ends of said pilot line, said buoys being of unequal buoyancy, and the upper buoy being provided with longitudinally-projecting legs straddling said pulley, and having its top formed of a plate forming a 95 cover for said chamber, substantially as described.

3. Apparatus of the character described, 100 comprising a chamber provided on the upper side of the boat, a pulley mounted in said chamber, a pilot line rove over said pulley and also mounted in said chamber, and a pair of buoys connected, respectively, to 105 the ends of said pilot line, said buoys being of unequal buoyancy, and the upper buoy being provided with longitudinally-projecting legs straddling said pulley, and having its top formed of a plate forming a cover for said chamber, the said plate being provided with detachable hinges connecting the 110 same at one end to said boat, and with a locking bar detachably connecting the other end of said plate to said boat, substantially as described.

4. Apparatus of the character described, 115 comprising a chamber provided on the upper side of the boat, said chamber being located between the upper deck and the top of the hull of said boat, and having its top flush with the upper deck, a pulley mounted 120 in said chamber, a pilot line rove over said pulley and also mounted in said chamber, and a pair of buoys connected, respectively, to the ends of said pilot line, said buoys being of unequal buoyancy, and the upper 125 buoy being provided with longitudinally-projecting legs straddling said pulley, and having its top formed of a plate forming a

cover for said chamber, the said plate being provided with detachable hinges connecting the same at one end to said boat, and with a locking bar detachably connecting the other 5 end of said plate to said boat, substantially as described.

5. Apparatus of the character described, comprising a chamber provided on the upper side of the boat, a pulley mounted in 10 said chamber, a pilot line rove over said pulley and also mounted in said chamber, and a pair of hollow corrugated sheet metal buoys connected, respectively, to the ends of 15 said pilot line, said buoys being of unequal buoyancy, and the upper buoy having its top formed of a plate forming a cover for said chamber, substantially as described. 75

6. Apparatus of the character described, comprising a chamber provided on the upper 20 side of the boat, a pulley mounted in said chamber, a pilot line rove over said pulley and also mounted in said chamber, and a pair of hollow corrugated sheet metal buoys connected, respectively, to the ends 25 of said pilot line, said buoys being of unequal buoyancy, and the upper buoy being provided with longitudinally-projecting legs straddling 30 said pulley, and having its top formed of a plate forming a cover for said chamber, substantially as described.

7. Apparatus of the character described, comprising a chamber provided on the upside of the boat, said chamber being located 35 between the upper deck and the top of the hull of said boat, and having its top flush with the upper deck, a pulley mounted in said chamber, a pilot line rove over said pulley and also mounted in said chamber, and a pair of hollow corrugated sheet metal 40 buoys connected, respectively, to the ends of said pilot line, said buoys being of unequal buoyancy, and the upper buoy having its top formed of a plate forming a cover for 45 said chamber, substantially as described.

8. Apparatus of the character described, comprising a chamber provided on the upper side of the boat, said chamber being located 50 between the upper deck and the top of the hull of said boat, and having its top flush with the upper deck, a pulley mounted in said chamber, a pilot line rove over said pulley and also mounted in said chamber, and a pair of hollow corrugated sheet metal buoys connected, respectively, to the ends of 55 said pilot line, said buoys being of unequal buoyancy, and the upper buoy being provided with longitudinally-projecting legs straddling 60 said pulley, and having its top formed of a plate forming a cover for said chamber, substantially as described.

9. Apparatus of the character described, comprising a chamber provided on the upper side of the boat, a pulley mounted in said chamber, a pilot line rove over said pulley

and also mounted in said chamber, and a 65 pair of hollow corrugated sheet metal buoys connected, respectively, to the ends of said pilot line, said buoys being of unequal buoyancy, and the upper buoy having its top 70 formed of a plate forming a cover for said chamber, the said plate being provided with detachable hinges connecting the same at one end to said boat, and with a locking bar detachably connecting the other end of said plate to said boat, substantially as described. 75

10. Apparatus of the character described, comprising a chamber provided on the upper side of the boat, a pulley mounted in said chamber, a pilot line rove over said pulley and also mounted in said chamber, and a 80 pair of hollow corrugated sheet metal buoys connected, respectively, to the ends of said pilot line, said buoys being of unequal buoyancy, and the upper buoy being provided with longitudinally-projecting legs straddling 85 said pulley, and having its top formed of a plate forming a cover for said chamber, the said plate being provided with detachable hinges connecting the same at one end to said boat, and with a locking bar detachably connecting the other end of said plate to said boat, substantially as described. 90

11. Apparatus of the character described, comprising a chamber provided on the upper side of the boat, said chamber being located 95 between the upper deck and the top of the hull of said boat, and having its top flush with the upper deck, a pulley mounted in said chamber, a pilot line rove over said pulley and also mounted in said chamber, 100 and a pair of hollow corrugated sheet metal buoys connected, respectively, to the ends of said pilot line, said buoys being of unequal buoyancy, and the upper buoy having its top formed of a plate forming a cover 105 for said chamber, the said plate being provided with detachable hinges connecting the same at one end to said boat, and with a locking bar detachably connecting the other end of said plate to said boat, substantially 110 as described.

12. Apparatus of the character described, comprising a chamber provided on the upper side of the boat, said chamber being located between the upper deck and the 115 top of the hull of said boat, and having its top flush with the upper deck, a pulley mounted in said chamber, a pilot line rove over said pulley and also mounted in said chamber, and a pair of hollow corrugated 120 sheet metal buoys, connected, respectively, to the ends of said pilot line, said buoys being of unequal buoyancy, and the upper buoy being provided with longitudinally-projecting legs straddling said pulley, and having 125 its top formed of a plate forming a cover for said chamber, the said plate being provided with detachable hinges connecting the same

at one end to said boat, and with a locking bar detachably connecting the other end of said plate to said boat, substantially as described.

5 13. A buoy for use in apparatus of the character described, comprising a corrugated sheet metal shell with internal bracing therefor.

10 14. A buoy for use in apparatus of the character described, comprising a shell made of sheet metal having a series of corrugations therein, and provided with internal bracing, the said bracing consisting of a series of stiffening tubes extending between 15 opposite sides of the shell.

20 15. A buoy for use in apparatus of the character described, comprising a shell made of sheet metal having a series of corrugations therein, and provided with internal bracing, the said bracing including a series 25 of trusses secured on the interior of said shell.

30 16. A buoy for use in apparatus of the character described, comprising a shell made of sheet metal having a series of corrugations therein, and provided with internal bracing, the said bracing including a series of trusses extending around the interior of said shell, and a series of stiffening tubes extending between opposite sides of said shell.

35 17. A buoy for use in apparatus of the character described, comprising a corrugated sheet metal shell with internal bracing therefor, the various joints in said shell being welded.

40 18. A buoy for use in apparatus of the character described, comprising a shell made of sheet metal having a series of corrugations therein, and provided with internal bracing, the said bracing consisting of a series 45 of stiffening tubes extending between opposite sides of said shell, the various joints in said shell being welded.

50 19. A buoy for use in apparatus of the character described, comprising a shell made of sheet metal having a series of corrugations therein, and provided with internal bracing, the said bracing including a series 55 of trusses secured on the interior of said shell, the various joints in said shell being welded.

60 20. A buoy for use in apparatus of the character described, comprising a shell made of sheet metal having a series of corrugations therein, and provided with internal bracing, the said bracing including a series of trusses extending around the interior of said shell, and a series of stiffening tubes extending between opposite sides of said shell, the various joints in said shell being welded.

21. A sheet metal buoy for use in apparatus of the character described, comprising a substantially bowl-shaped body por-

65 tion and two laterally-extending legs connected thereto, substantially U-shaped in cross-section, and a continuous plate forming the top of said body portion and said legs, the said plate, and said body portion, and said legs being corrugated.

70 22. A sheet metal buoy for use in apparatus of the character described, comprising a substantially bowl-shaped body portion and two laterally-extending legs connected thereto, substantially U-shaped in cross-section, and a continuous plate forming the top of said body portion and said legs, the said body portion, and the said legs being provided with internal bracing.

75 23. A sheet metal buoy for use in apparatus of the character described, comprising a substantially bowl-shaped body portion and two laterally-extending legs connected thereto, substantially U-shaped in cross-section, and a continuous plate forming the top of said body portion and said legs, the said body portion and the said legs being provided with internal trusses.

80 24. A sheet metal buoy for use in apparatus of the character described, comprising a substantially bowl-shaped body portion and two laterally-extending legs connected thereto, substantially U-shaped in cross-section, and a continuous plate forming the top of said body portion and said legs, and 85 said body portion being braced by a series of tubes connecting the opposite sides of the shell of the buoy.

90 25. A sheet metal buoy for use in apparatus of the character described, comprising a substantially bowl-shaped body portion and two laterally-extending legs connected thereto, substantially U-shaped in cross-section, and a continuous plate forming the top of said body portion and said legs, the 95 said plate, and said body portion, and said legs being corrugated, and means carried by the said plate for detachably connecting said buoy to the hull of the boat.

100 26. A sheet metal buoy for use in apparatus of the character described, comprising a substantially bowl-shaped body portion and two laterally-extending legs connected thereto, substantially U-shaped in cross-section, and a continuous plate forming the 105 top of said body portion and said legs, the said body portion, and the said legs being provided with internal bracing, and means carried by the said plate for detachably connecting said buoy to the hull of the boat.

110 27. A sheet metal buoy for use in apparatus of the character described, comprising a substantially bowl-shaped body portion and two laterally-extending legs connected thereto, substantially U-shaped in cross-section, and a continuous plate forming the 115 top of said body portion and said legs, the said body portion and the said legs being

provided with internal trusses, and means carried by the said plate for detachably connecting said buoy to the hull of the boat.

28. A sheet metal buoy for use in apparatus of the character described, comprising a substantially bowl-shaped body portion and two laterally-extending legs connected thereto, substantially U-shaped in cross-section, and a continuous plate forming the

top of said body portion and said legs, and said body portion being braced by a series of tubes connecting the opposite sides of the shell of the buoy, and means carried by the said plate for detachably connecting said buoy to the hull of the boat.

15 In testimony whereof I affix my signature.

DANIEL WILLIAM SHEA.
